UNITED STATES PATENT OFFICE.

FRANK C. HINCKLEY, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

RECORDING ATTACHMENT.

1,291,515.

Specification of Letters Patent. Patented Jan. 14, 1919.

Application filed October 27, 1915. Serial No. 58,176.

To all whom it may concern:

Be it known that I, FRANK C. HINCKLEY, a citizen of the United States of America, residing in Bridgeport, Connecticut, (whose 5 post-office address is care American Graphophone Company, Bridgeport, Connecticut,) have invented a new and useful Improvement in Recording Attachments, which invention is fully set forth in the following 10 specification.

This invention relates to talking-machines, and is primarily intended to be employed with machines which play disk records and which do not already have means for making a record in the first instance. Broadly, 15 the present invention consists of an improved attachment to be applied to such disk machines, so that records can be made thereon, although the spirit of the invention could 20 be embodied in an attachment applicable to a cylinder machine if desired; and the attachment of course can be used for reproducing also.

The preferred embodiment of the invention 25 comprises the combination of three parts, first, a bracket (detachably) secured to the bed-plate or cabinet of the talking-machine and supporting the feed-screw, with a recorder (or reproducer) in operative relation to the recording-tablet; second, a 30 block or bushing (detachably) secured to the turn-table of the machine, for engaging a suitable recording-tablet and also for transmitting the rotary movement of the main shaft and turn-table to the feed-mechanism aforesaid; and, third, suitable means for 35 transmitting said rotary motion to said feed-mechanism. If desired the block or bushing might be dispensed with and the feed-mechanism rotated directly from the recording-tablet or the turn-table. Preferably the 40 invention further includes a provision of flexibility in said transmission-means, so that the feed-screw can be properly rotated even though not positioned in precise alignment 45 with the axis of the turn-table. And, finally, the invention consists further of the features of construction and arrangement hereinabove more particularly pointed out 50 and claimed.

Although the invention may be embodied in various forms, it will be best understood by reference to the accompanying drawings and the following description of a preferred 55 embodiment applied to a disk talking-ma-

chine; but it must be understood that the drawings and description are not intended to limit the invention but merely to illustrate one embodiment thereof.

In these drawings,—

Figure 1 represents a plan of a portion of a conventional disk talking-machine equipped with the new attachment;

Fig. 2 is a front elevation of the construction shown in Fig. 1, but partly in vertical 65 section and showing the clutch members, separated; and

Fig. 3 is a transverse vertical section, also showing in elevation the worm and a portion 70 of the worm-gear.

Referring to these drawings, 1 is an ordinary or any suitable boxing or cabinet for a disk talking-machine, which has the usual turn-table 2 carried by the motor-shaft whose upper end projects at 3, all as usual. 75 Upon the center of the turn-table is laid a block 4, preferably circular, which has one or more upwardly extending studs 5 to constitute a clutch-plate for rotating the feed-mechanism, as hereinafter described. These 80 studs are preferably carried by a split-spring bushing 6 secured centrally in the block 4, by means of which the block may be held firmly upon the projecting end 3 of the motor shaft. Preferably the block 4 is 85 provided with an annular groove around its circumference, in which is seated a band 7 of rubber or the like; and a flat recording-tablet 8, of suitable recording-material, and having a central opening adapted to snugly 90 embrace the band 7, may then be put in position as indicated in Figs. 1 and 2.

Upon the cabinet 1 is screwed a bracket 9 carrying a vertical post 10 upon which is mounted the frame carrying the feed-mechanism. As shown, this frame comprises two vertical end-pieces or heads 11 and 12, held together by three horizontal rods. Integral with head 11 is a vertical sleeve 13 that fits upon post 10; and preferably the lower end 100 of the sleeve is cut away diagonally to engage a pin 14 upon the post, whereby gravity tends to bring the frame into proper position above the turn-table, more or less radially thereof, while horizontal swinging 105 movement of the frame tends to lift it slightly, whereby the elements supported thereby are disconnected from the turn-table-supported elements. If desired, a thumb-nut 15 may be employed to hold the 110

frame rigidly in any desired adjustment across the turn-table.

Two of the connecting-rods may be solid; but the third, as 16, is hollow and longitudinally-slotted to receive the feed-screw 17 (see Fig. 3) and permit the partial feed-nut to engage therewith in the usual manner. The outer end of the screw-shaft projects beyond the head 12 and carries the 10 worm-gear 18. The usual or any suitable carriage 19 for carrying a sound-box, preferably one adapted to carry interchangeably either a recorder or a reproducer, slides upon the hollow rod 16 and one or both of 15 the other two rods, and is equipped with the usual partial-nut for entering said longitudinal slot and engaging said feed-screw, and is also provided with the usual lever 20 for simultaneously lifting the recorder 20 (or reproducer) and disengaging said nut.

In suitable bearings 21, upon the free side of the head 12, is journaled a hollow vertical shaft 22, carrying externally a worm 23 in mesh with said worm-gear 18. A volute 25 helical spring 24 is secured at its smaller and upper end to this worm-shaft 22, and at its lower and larger end to a horizontal plate 25. A headed lifting rod 26 is splined in the bore of the worm-shaft to telescope 30 therein, and at its lower end is provided with a disk-like foot which extends under the overhanging rim 27 secured to plate 25, but is not otherwise connected thereto. Upon the lower face of this plate 25 are two 35 or more depending studs adapted to engage against the sides of the studs 5 aforesaid, so that plate 25 constitutes an upper clutch-plate adapted to co-act with the lower clutch-plate aforesaid; and, if desired, said 40 plate 25 may have a depending central boss adapted to enter the bore in the lower clutch-member. The spring 24 and the non-positive connection between rod 26 and plate 25 constitute a flexible or resilient connection 45 by which the worm-shaft will be properly rotated even if not precisely concentric with the axis of the turn-table and main shaft 3.

Although, as stated, any usual or suitable carriage and recorder (or reproducer) may 50 be employed, yet in Fig. 3 is illustrated a preferred structure for this service, in which the neck or stem of the recorder (or reproducer) 28 is shown as detachably seated in the usual trunnion-socket that swings vertically upon the horizontal pivot 29 upon the carriage, and is provided with the upwardly-extending lifting-arm 30. The lifting-lever 20 is shown as the handle of a ring which journals around the usual sleeve slidable 55 upon one of the guide-rods, and is provided with two cam-surfaces. Two levers are journaled upon the same transverse pivot 31 in the carriage, of which the substantially-vertical lever 32 is adapted at its 60 upper end to be acted upon by one of the

two cams aforesaid, while its lower end is located adjacent said lifting-arm 30, so that the shifting of the handle 20 to the left (in Fig. 3) will shift the upper end of arm 32 to the right and thereby lift the recorder 70 (or reproducer) clear from the tablet 8. The other or substantially-horizontal lever 33 is adapted to be depressed at its left by the second cam aforesaid, and at its right carries the usual partial-nut adapted to pass 75 through the longitudinal slot in hollow rod 16 and engage the feed-screw 17, so that the shifting of the handle 20 to the left (in Fig. 3) not only depresses the rear end of said lever 33 and thereby disengages the 80 feed-nut but also lifts said recorder (or reproducer) clear from the recording-tablet, thus putting the recorder or reproducer into inoperative position so that the operator can freely shift it along its frame-work; while 85 shifting handle 20 to the right (in Fig. 3) restores the parts to their operative position, preferably by aid of a double spring such as 34, secured at its center to the carriage and bearing at one end against the 90 upper end of lever 32 and at its other end against the outer end of lever 33.

The invention has thus been set forth with considerable detail, but only for the sake of clearness since it is not limited to the precise construction and arrangement above set forth. It must be understood that the invention may be embodied in various forms, that parts of the structure can be inverted, or can be transposed with other parts, and that parts can be used to the exclusion of other parts, without in any case departing from the spirit of the invention.

The invention having thus been fully set forth, what is claimed is;

1. The combination with a disk talking-machine comprising a motor and a turn-table, of an attachment therefor consisting of a bracket carrying a frame supporting a feed-screw and a carriage propelled thereby, 110 a sound box upon said carriage, and means comprising a resilient connection actuated from said motor for rotating said feed-screw.

2. The combination with a disk talking-machine comprising a motor and a turn-table, of an attachment therefor comprising a bracket carrying a frame supporting a feed-screw and a carriage propelled thereby, 120 a sound-box upon said carriage, and means comprising a helical spring actuated from said motor for rotating said feed-screw.

3. The combination with a disk talking-machine comprising a motor and a turn-table, a block secured centrally upon said 125 turn-table to engage a tablet thereon, a bracket secured to the talking-machine and carrying a frame supporting a feed-screw and a carriage propelled thereby, a sound box upon said carriage, and means compris- 130

ing a resilient connection actuated from said block for rotating said feed-screw.

4. An attachment for disk-talking-machines, comprising a clutch-plate secured centrally with respect to the turn-table thereof, a bracket mounted upon the machine at one side of its turn-table, a feed-screw supported by said bracket and extending substantially radially above said turn-table, a carriage propelled by said feed-screw and supporting a sound box, a vertical shaft rotatably connected to said feed-screw, and resilient connections between said shaft and said clutch-plate whereby rotation of 15 said turn-table rotates said feed-screw.

5. An attachment for a disk talking-machine, comprising a clutch-plate secured centrally with respect to the turn-table thereof, a bracket mounted upon the machine at one 20 side of its turn-table, a feed-screw supported by said bracket and extending substantially radially above said turn-table, a carriage propelled by said feed-screw and supporting a sound box, a vertical shaft 25 rotatably connected to said feed-screw, and flexible connections comprising a helical spring between said shaft and said clutch-plate whereby rotation of said turn-table rotates said feed screw.

30 6. In combination with a disk talking machine, a clutch-plate located centrally with respect to the turn-table, a feed-screw located substantially radially of said turn-table, a carriage propelled by said feed-screw and adapted to carry a sound box, a hollow vertical worm in mesh with a gear connected with said feed-screw, a telescoping rod splined in said worm, a second clutch-plate loosely engaging the foot of said rod 35 and adapted to engage the first-named clutch-plate, and a helical spring encircling said rod and connected at its two ends to said worm and said second clutch-plate respectively.

45 7. In combination with a block or bushing adapted to be detachably secured centrally upon a turn-table and carrying a clutch-plate, a feed-screw located substantially radially of said turn-table, a carriage propelled by said feed-screw and adapted to carry a sound box, a hollow vertical worm in mesh with a gear connected with said feed-screw, a telescoping rod splined in said worm, a second clutch-plate loosely engaging the foot of said rod and adapted to engage the first-named clutch-plate, and a helical spring encircling said rod and connected at its two ends to said worm and said second clutch-plate respectively.

50 8. The combination with a disk talking-machine comprising a turn-table, of an attachment therefor comprising a bracket mounted on the machine at one side of the turn-table, a frame carrying a feed-screw 55 and a sound-box-carriage propelled thereby,

said frame having a rotatable connection with said bracket whereby said frame may swing in a plane substantially parallel to the turn-table, means actuated from the motor talking machine for rotating said feed-screw, and means intermediate said bracket and frame whereby rotation of the frame to or from radial relation to the turn-table causes movement of said frame toward or away from the turn-table. 70

9. The combination with a disk talking-machine comprising a turn-table, of an attachment therefor comprising a bracket mounted on the machine at one side of the turn-table, a frame carrying a feed-screw and a sound-box-carriage propelled thereby, said frame having a rotatable connection with said bracket whereby said frame may swing in a plane substantially parallel to the turn-table, means actuated from the motor talking machine for rotating said feed-screw and comprising a clutch, and means intermediate said bracket and frame whereby rotation of the frame to or from radial relation to the turn-table causes movement of said frame toward or away from the turn-table, respectively connecting or disconnecting the members of said clutch. 80

10. The combination with a disk talking machine comprising a turn-table, of an attachment therefor comprising a bracket mounted on the machine at one side of the turn-table, a frame carrying a feed-screw and a sound-box carriage propelled thereby, said frame having a rotatable connection with said bracket whereby said frame may swing in a plane substantially parallel to the turn-table, means actuated from the talking machine motor for rotating said feed-screw, and means intermediate said bracket and frame whereby said frame normally tends to swing to a position radial with respect to said turn-table. 90

11. In combination with a disk talking machine, a clutch-plate located centrally with respect to the turn-table, a feed-screw located substantially radially of said turn-table, a carriage propelled by said feed-screw and adapted to carry a sound-box, a vertical shaft, gearing between said shaft and feed-screw, a second clutch-plate loosely 110 engaging the foot of said shaft and adapted to engage the first-named clutch-plate, and a spring connected at its opposite ends to said shaft and said second clutch-plate respectively. 115

12. In a talking machine, a feed-screw, a carriage propelled thereby, a sound-box upon said carriage, and coaxial levers for raising said sound-box from operative relation to a tablet and for disconnecting the carriage from said feed-screw respectively. 125

13. In a talking machine, a feed-screw, a carriage propelled thereby, a sound-box upon said carriage, coaxial levers for raising 130

said sound-box from operative relation to a tablet and for disconnecting the carriage from said feed-screw respectively, and a single means for actuating said levers.

5 14. In a talking machine, a feed-screw, a carriage propelled thereby, a sound-box upon said carriage, coaxial levers for raising said sound-box from operative relation to a tablet and for disconnecting the carriage from said feed-screw respectively, a single means for actuating said levers, and a single spring opposing movement of said levers in one direction.

15 15. In a talking machine, a feed-screw, a carriage propelled thereby, a sound-box upon said carriage, a pair of levers for raising said sound-box from operative relation to a tablet and for disconnecting the carriage from said feed-screw, and a single 20 spring normally maintaining said carriage in operative relation to said feed-screw and said sound-box-raising lever out of operative position.

16. In a talking machine, a feed-screw, a

carriage propelled thereby, a sound-box 25 upon said carriage, a pair of levers for raising said sound-box from operative relation to a tablet and for disconnecting the carriage from said feed-screw, a single spring normally impelling said levers in one direction, and a single cam means for moving said levers in the opposite direction.

17. The combination with a turn-table, of a bracket mounted at one side of the turn-table, a feed-screw rotatably supported 35 by said bracket, a sound-box carriage propelled by said feed-screw, and connections for rotating said feed-screw from the turn-table spindle comprising a clutch and a spring operatively connected at opposite 40 ends to said screw and clutch.

In testimony whereof I have signed this specification in the presence of two subscribing witnesses.

FRANK C. HINCKLEY.
